HARRY BLOUNT, OF OAK PARK, ILLINOIS, ASSIGNOR TO WESTERN ELECTRIC COMPANY, INCORPORATED, OF NEW YORK, N. Y., A CORPORATION OF NEW YORK

DRILLING MECHANISM

Application filed April 11, 1930. Serial No. 443,316.

This invention relates to a drilling mechanism and more particularly to a mechanism for drilling a plurality of bodies, such as diamond dies.

5 An object of the invention is the provision of a compact and efficient mechanism for drilling a body.

One embodiment of the invention contemplates the provision in a diamond die drilling machine, upon an exterior sleeve of a central vertical pedestal, of a plurality of sets of drill and die spindles, the former being driven through friction pinions from a drive wheel rotated by a vertical shaft within the pedestal. The die spindles are reciprocated vertically between rollers by a spring and cam arrangement actuated from the vertical shaft and are individually readily removable from the machine. A cutting liquid is intermittently delivered to each of the dies from a common reservoir and pumped back thereto by a mechanically operated diaphragm.

A better understanding of the invention will be had from the following detailed description, read in connection with the accompanying drawings forming a part thereof, in which

Fig. 1 is a fragmentary vertical section of 30 a multiple unit drilling machine constituting one embodiment of the invention;

Fig. 2 is a plan section taken on the line 2—2 of Fig. 1;

Fig. 3 is an enlarged section taken on the 35 line 3—3 of Fig. 1 showing details of the drilling unit;

Fig. 4 is an enlarged section taken on the line 4—4 of Fig. 1; and

Fig. 5 is a fragmentary enlarged section 40 taken on the line 5—5 of Fig. 1 showing further details of the drilling unit.

Referring to the drawings, wherein similar parts are indicated by identical reference numerals, a pedestal base 10 (Fig. 1) 45 supports a multiple unit drilling machine, generally designated by the numeral 11, upon a conventional type of bench 12. A plurality of identical drilling units 14, in the particular embodiment, ten such being shown, 50 are mounted in the machine, each including

a U-shaped rocker arm 15 which supports a drilling spindle 16 and in aligned relation thereto, a die spindle 18. The rocker arms 15, 15 are mounted upon the periphery of a normally stationary exterior sleeve 19 of 55 the machine by means of individual brackets 20, 20, the arms being pivotally attached thereto by means of a pin 22. An upper end of the U-shaped arm is formed with a tubular portion 23 which accommodates a 60 slideable sleeve 24, within which is rotatably mounted the drilling spindle 16. A drilling needle or point 27 of any conventional type appropriate for the drilling of blanks or diamond dies is provided upon the lower 65 end of the spindle 16. Upon the upper end of the drilling spindle a friction pinion 28 is formed for the purpose of actuating the drill in a manner to be described hereafter. A circular shelf 30 is formed upon the upper 70 end of the exterior sleeve 19 and is provided with suitable peripheral spaced recesses 31 for the purpose of accommodating the tubular portion 23 of the rocker arms.

The exterior sleeve is provided with a central aperture 32 through which extends a stationary sleeve 34, having at its lower extremity a flange 35 by means of which the interior sleeve is secured to the pedestal base 10 with a plurality of suitable bolts 36. At its 75 upper extremity the interior sleeve has suitably secured thereto an annular member or collar 38 by means of which the exterior sleeve is held in position with respect to the interior sleeve. Ball bearings 39, 39 are 80 mounted within the stationary sleeve 34 and at either extremity, for the purpose of supporting and permitting free rotation therein of a shaft 40, which extends axially of the interior sleeve. A friction wheel 42 is 85 mounted upon the shaft 40 above the sleeve and is of sufficient diameter to cause it normally to engage the friction pinion 28 of the drilling spindles. At its lower end, the shaft 40 is provided with a coupling 43 90 of any conventional type which connects thereto a motor shaft 44, of any suitable type of motor 46, for the purpose of driving the apparatus. At its lower portion and directly above the flange 35 of the interior sleeve 100

the exterior sleeve is provided with a recess 47 within which is seated a relatively stiff compression spring 48 by force of which a pin or ball 50 is held in normal engagement with any desired one of a plurality of spaced depressions 51, 51 formed in the upper face of the flange 35.

The rocker arms are maintained in such a position as to cause the friction pinions 28 to normally engage the friction wheel 42 by means of a compression spring 56. The spring is seated within a hollow pin 54 extending axially through a substantially horizontal and internally threaded aperture 52 in the rocker arm, and is compressed between the pin and a threaded nut 58. It will be understood that the pin is thrust against the outer surface of the exterior sleeve, the tendency being to thrust the lower portion of the rocker arm away from the sleeve and the upper portion of the arm toward the sleeve with the result that the force of the spring maintains the friction pinion against a bearing surface 57 of the friction wheel. The threaded nut 58 is formed with a slotted head 61 by means of which its position within the aperture may be altered to vary the pressure between the friction pinions and the bearing surface 57 as desired.

A mounting cup 59, for supporting a blank or die 60 during drilling, is secured upon the upper end of the die spindle 18. The die spindle 18 is movably supported by a spindle mounting block 62 upon a face 63 of which (Figs. 1 and 5) are mounted a pair of vertically aligned grooved rollers 64—64, rotatably mounted upon stationary pins 65—65. Substantially horizontally opposite to the pins 65 are provided a pair of cylindrical plugs 66—66 which extend through the mounting block from front to rear thereof and which are rotatable therein. The plugs are provided upon the front ends thereof with off-centered stationary pins 67 upon which are mounted grooved rollers 68—68. Secured to each plug at the rear end thereof is an annular rim 70 formed with an arm 71; and the arms of the upper and lower plugs are connected by a single connecting rod 72, whereby any movement of one of the plugs is reflected in and controlled by movement of the other plug so that they rotate in unison. It will be observed that rotation of the cylindrical plugs will result in movement of the pins 67 either toward or away from the rollers 64. However, springs 74—74 connect either end of the connecting rod 72 to the block, thus requiring that the rollers be maintained normally in such a position as to cause the rollers 68 and 64 to engage between them the die spindle 18, and to permit its movement therebetween. Mounted upon ears 75 on the lower surface of the rocker arm is a pin 76, to which is secured one end of a leaf spring 78, the other end of which rests upon a key

79 rigidly secured to the die spindle 18. It will be understood that the tendency of the spring is continually to urge the spindle downwardly.

A gear 80 is keyed to the shaft 40 between the coupling 43 and the lower ball bearings 39, and meshes with an intermediate gear 82 mounted upon a shaft 83 which is secured in the flange 35 of the interior sleeve. The flange is provided with a peripheral recess 84, in which is rotatably mounted a ring gear 86, having internal teeth 87, which mesh with the intermediate gear, in such manner that the ring gear is driven in accordance with the rotation of the shaft 40 about the pedestal. At spaced points upon the periphery of the ring gear a plurality of projecting roller lobes 88 are affixed. The exterior sleeve is provided with a lower circular shelf 91 upon the lower surface of which, at each drilling unit, is secured a pin 92, to which is rotatably secured a lever 93 having a ledge 94. The shelf is provided near the periphery thereof with spaced apertures 96 through each of which slidably extends a pin 95, which normally rests upon the ledge of the lever. Upon the opposite end of the lever from the ledge a roller 98 is mounted and, adjacent thereto, the lever is provided with a compression spring 99 which is seated within a hollow adjustable threaded member 100 which extends through a threaded aperture 102 through the lower circular shelf directly above the lever. It will be understood that the pressure of the spring 99 is sufficient to overcome the weight of the die spindle and pin 95 and to maintain the roller 98 in contact with the lobes 88 when they pass thereunder. It will also be noted that the pressure of the spring 99 is sufficient to secure the proper pressure between the needle and the die.

A cylindrical cover 103 encloses the multiple unit drilling machine at the upper portion thereof and consists of a top portion 104 and sides 106. The top 104 is provided with a central aperture 105 within which rests a conical reservoir 107 which is firmly secured to the top 104 by suitable clamps 108—108. This reservoir is for holding and forwarding a supply of cooling, lubricating or cutting fluid 109 to each of the drilling units. This is accomplished by providing, near the bottom of the conical reservoir and upon the same horizontal level with each other, ten outlets or tubes 110, each of which is provided with an individual tubing 111 which extends downwardly from the outlet and through a vertical aperture 112 (Fig. 2), with which the upper vertical shelf 30 is provided. It will be noted that the apertures 112 are positioned immediately adjacent the peripheral recesses 31. This is in order that after passing therethrough the tube may extend downwardly beside the tubular portion 130

23 and beside the drilling needle 27, and rest within the mounting cup 59 when it has been raised to present the die blank to the drilling needle. The conical reservoir 107 is provided with a flexible lid or diaphragm 114 which is held thereon as to be airtight by the clamps 108. Downwardly through the center of the diaphragm extends a plunger rod 115 which is secured to the diaphragm and bears upon its lower extremity the plunger 116. As shown in Fig. 4 the plunger is provided with a number of peripheral notches 118 in order to permit flow of the fluid 109 with reference thereto without clogging. Mounted in the cylindrical sides 106 of the cover is a rotatable shaft 119 which has keyed thereto approximately at the center a bevel gear 120 which meshes with and is driven from a similar bevel gear 122 keyed to the upper extremity of the central drive shaft 40. To one end of the shaft 119 a worm 123 is keyed, which meshes with a worm wheel 124 mounted upon a shaft 126 positioned above the worm. The worm wheel 125 is provided with a cam portion 127. Upon one of the clamps 108 a bracket 128 is mounted, in which is pivotally mounted an arm 130 upon one end of which is secured the upper end of the plunger rod 115 and upon the other end of which is secured a tensioning spring 131, the tendency of which is to maintain the plunger rod 115 in such a position that a substantial portion of the mass of the plunger 116 is withdrawn from the fluid 109, in which condition no fluid will pass downwardly through the tubing. The arm 130 is tilted to operate the plunger by the cooperation with the lead of the cam of a rod 132 which extends vertically through the cover, and a guide sleeve 134 mounted thereon, to engage the arm 130.

The slidable sleeve 24 is provided with a series of teeth 135 upon one side thereof which are engaged by the teeth of a pinion 136 (Figs. 1 and 3) which is rotatably mounted in the tubular portion 23. The pinion is rotated by means of a projecting knurled rim 138, by means of which the slidable sleeve may be raised or lowered manually. For the purpose of loosening or stiffening the action of the sleeve, a threaded manually adjustable bolt 139 is provided which engages a threaded aperture 137 of the rocker arm and which may be either tightened or removed from contact with the body of the sleeve in order to permit its control.

At each of the recesses 31 and threaded in the circular shelf 30, an adjusting bolt 140 is provided by means of which wearing of the friction surface 57 and of the pinion 28 may be compensated for. An outwardly spring-pressed latch member 142 is slidably mounted in the upper portion of each U-shaped rocker arm, and is provided with a finger 143 which projects to the exterior of

the rocker arm through a slot 144 formed therein. When the rocker arm is in the position shown in Fig. 1 and the unit is in normal operation with the spindles being driven, the latch member 142 is depressed within the rocker arm, the upper end of the latch member abutting the under surface of the shelf 30.

A plurality of manually controlled cut-off screws 145 (Figs. 1 and 2) are mounted upon the periphery of the upper shelf and extend through the sides 106 of the cover and to the apertures 112 and contact with the tubing 111, by means of which the flow of fluid through the tubing may be controlled.

From the foregoing it will be understood that all of the drilling units are driven by the motor 46 through the shaft 40 which rotates the friction wheel 42 to drive the drilling spindles through the friction rollers 28 and at the bottom drives the ring gear 84, the lobular cam rollers of which actuate the lever 93 to cause the alternate raising and lowering of the die spindle 18. The spacing of the cam rollers 88 is determined under conventional practice, the cams lifting the roller 98 of the lever to lower the die spindle and die away from the drilling point 27, when it is desirable that the drill point address the die anew. After a cam roller 88 has passed the lever roller 98, the latter is depressed by the spring 99 and remains in such position until lifted by the next cam roller 88 during which interval the pin 95 is raised upon the lever ledge 94 and the die 60 is subjected to the drilling point.

The fluid 109 may consist of a mixture of alcohol and diamond dust, which has been found to be an efficient cutting compound. One method of employing such a cutting fluid is well known in the art, having been described and claimed in Patent No. 1,677,172 issued on July 17, 1928 to Frederick W. Colbeck and Sigurd Thronsen. In the particular instance, the alternate supplying and withdrawal of the cutting liquid simultaneously and continuously with respect to a plurality of drilling units is effected by means of the bevel gear 120 meshing with the bevel gear 122 of the shaft 40 and rotating the shaft 119 to drive the worm 123. The worm wheel 124 is rotated thereby causing the cam 127 to alternately raise and lower the cam pin 132. When the pin 132 is in the pit of the cam's lead, the tension spring 131 pulls the lever to cause the diaphragm 114 to expand, thus lowering the pressure within the reservoir and drawing the plunger 116 above the surface of the liquid with the double effect of lowering the level of the liquid below the tubular openings 110, thus preventing liquid from flowing therethrough inwardly into the tubing 111 and, due to the decrease in pressure, withdrawing the liquid in the mounting cup 59 upwardly through the tub-

ing 130

ing 111 and into the reservoir. As the wheel 124 is revolved and the pin 132 attains the crest of the cam's lead, the diaphragm 114 is depressed against the tension of the spring 131, the plunger falls into the liquid and displaces a quantity thereof, which is squirted downwardly through the tubing 111 due to the increased pressure within the reservoir.

10 It will be seen that the operation of the apparatus in the three phases just described is regular and normally continuous with respect to each of the drilling units. From time to time, however, it is desirable to stop 15 the operations with respect to one or more of the units without interrupting the working of the remaining units, as for instance, when it is desired to inspect a die being drilled to determine its condition as to completion. This may be readily accomplished 20 by a single workman who, without changing his station, may grasp that unit which is within most convenient reach and thrust it manually to one side so as to force the ball 25 50 from the particular depression 51 in which it is seated and forcibly rotate the exterior sleeve with respect to the interior sleeve until that unit to which he desires access is as close at hand as desired. The workman then 30 rotates the sleeve 30 in either direction a sufficient distance to cause the ball 50 to engage in another one of the locking depressions 51, thus securing the units in position 35 so as to permit their continued normal operation in the manner described above.

By adjusting the cut-off screw 145, the operator then stops the flow of cutting fluid to the die under inspection. By means of the knurled cap 138, he then rotates the pinion 40 136 which engages the teeth 135 to raise the slidable sleeve 24. The drilling spindle 16 and the friction pinion upon the upper end thereof are thus raised with the sleeve until the pinion rises above the friction surface 57 45 of the wheel 42, thus stopping the rotation of the drilling spindle 16 and providing ample room beneath the drilling point 27 for access to the mounting cup 59. The operator then grasps the upper portion of the rocker 50 arm and pulls it outwardly from the recess 31, the arm pivoting at 22. The latch member 142 is expelled by its spring from the body 55 of the arm and projects in front of the bolt 140 and maintains the arm in tilted position 60 against the pressure of the spring 56. The rocker may be replaced in the recess 31 by 65 pressing the finger 143 downwardly against its spring and pressing the tubular portion inwardly, to cause the latch member to again engage the under surface of the shelf 30. The outward tilting movement of the rocker arm moves the die spindle 18 out of alignment 70 with the reciprocating pin 95, thus stopping the reciprocation of the die spindle. The tension of the leaf spring 78 thereby becomes

effective upon the key 79 causing the die spindle to fall downwardly until the mounting cup has reached the lowest extent of its travel, thus providing additional space thereabove. In case the die is found to have been 70 completely formed and it is desired to supplant it with a new blank, or in case it is desired for any other reason to remove the die spindle from the unit, this is easily accomplished by the operator grasping the connecting rod 72 and pulling it downwardly as 75 shown in Fig. 5. This results in a counter-clockwise rotation of the cylindrical plug 66 causing the rollers 68-68 to be moved away from the rollers 64-64 and permitting the 80 easy withdrawal of the die spindle between the sets of rollers.

The spindle may be replaced in a corresponding manner by pulling the connecting rod 72 downwardly and inserting the new 85 spindle between the rollers and releasing the connecting rod, thus permitting the spring 74 to draw the rollers 68 into proper position so that the spindle is properly positioned between the rollers 68 and the rollers 64. 90 When this is accomplished and when it becomes desirable to resume operations with the unit, the operator rotates the pinion 136 to draw the slidable sleeve and enclosed spindle 16 downwardly into a normally operative 95 position. He then releases the latch 143 and lowers the finger 142, thus permitting the spring 56 to become effective to restore the tubular portion 23 within the recess 31 and effect operative engagement between the friction pinion 28 and the wheel 42. By this movement the die spindle 18 becomes realigned with the reciprocating pin 95 and when the operator releases the cut-off screw 145 to permit reestablishment of the flow of 100 cutting fluid into the mounting cup, the unit is once more in operation.

By use of the apparatus described, whereby the continuous operation of the drill spindles, the reciprocation of the die spindles and the intermittent and reversible action of the cam operated pumping system whereby cutting fluid is distributed to each of the multiple units and withdrawn therefrom by suction, a very efficient and compact machine is 110 presented by means of which operation of the plurality of spindles is secured from one motor, and control of the units individually and collectively by one workman is made 115 practicable.

What is claimed is:

1. In a drilling mechanism, a member for holding the object to be worked and formed to hold cutting fluid about the object, means for performing work upon the object, means for actuating the working means, a reservoir containing a supply of cutting fluid, means fastened to the reservoir for directing fluid therebetween and the object holder, a diaphragm affixed to the reservoir, a plunger 125

connected with the diaphragm for regulating the height of fluid in the reservoir, and means connected with the actuating means and operable in response thereto for controlling the movements of the plunger and the actuations of the diaphragm to cause predetermined quantities of fluid to be transmitted to the object holder at predetermined intervals and after use therein portions thereof to be returned to the reservoir over the same path at predetermined intervals.

2. In a mechanism for drilling objects, a member for holding an object to be worked and formed to hold cutting fluid about an object, means for performing work on an object, means for actuating the working means, a reservoir containing a supply of cutting fluid, means entirely enclosed and fastened to the reservoir for directing the fluid therebetween and the object holder, a diaphragm affixed to the reservoir, a plunger attached to the diaphragm for controlling the height of the fluid in the reservoir and the movements of the diaphragm, a spring, a centrally pivoted lever having one end connected with the plunger and the opposite end thereof secured to the spring, and cam means engaging the lever and actuating means and operable in response to the actuating means to cooperate with the spring for controlling the movements of the lever for periodically actuating the plunger and diaphragm to cause fluid to be transmitted through the directing means to the object holder and thereafter to cause a portion thereof to be returned to the reservoir over the same path.

3. In a mechanism for drilling objects, a plurality of holders for containing a cutting fluid about an object, a plurality of means for simultaneously drilling objects, common means for actuating the drilling means, a reservoir for containing a supply of cutting fluid, a plurality of common outlet and inlet tubes formed in the reservoir, a plurality of enclosed means attached to the tubes for directing the fluid between the reservoir and the object holders, means associated with the directing means for selectively restricting the movement of the fluid therethrough, a diaphragm affixed to the reservoir, a plunger attached to the diaphragm for controlling the level of the fluid in the reservoir and the movements of the diaphragm, and means connected with the actuating means and operatively responsive thereto for controlling the movements of the plunger to actuate the diaphragm for varying the pressure in the reservoir to cause the simultaneous transmission of predetermined amounts of fluid from the reservoir through the selectively controlled directing means to the object holders and thereafter simultaneously returning portions thereof through the same directing means to the reservoir.

4. In a mechanism for drilling objects, a

holder adapted to hold an object enveloped in a cutting fluid, means for working an object, means for actuating the working means, a reservoir containing a supply of cutting fluid, a conduit affixed to the reservoir for directing the fluid therebetween and the object holder, a diaphragm secured to the reservoir, a plunger attached to the diaphragm for controlling the level of fluid in the reservoir and movements of the diaphragm, and means connected with the actuating means and operable in response thereto for moving the plunger and actuating the diaphragm to regulate the pressure within the reservoir so that variations in pressure cooperate with movements of the plunger to cause predetermined quantities of fluid to be transmitted from the reservoir through the conduit to the object holder at predetermined intervals and thereafter to return portions thereof through the same conduit to the reservoir at predetermined intervals.

In witness whereof, I hereunto subscribe my name this 2nd day of April, A. D., 1930.
